UNITED STATES PATENT OFFICE.

FREDRICK WILLIAM FRANK, OF CHICAGO, ILLINOIS.

FIRE-DOOR.

1,120,189.

Specification of Letters Patent.

Patented Dec. 8, 1914.

Application filed November 11, 1911. Serial No. 659,773.

To all whom it may concern:

Be it known that I, FREDRICK WILLIAM FRANK, a citizen of the United States, residing at Chicago, in the county of Cook and State of Illinois, have invented a new and useful Improvement in Fire-Doors, of which the following is a specification.

This invention relates to fire doors, and it is especially designed for use in connection with locomotives, or large engine furnaces, although the door can be adapted for use in connection with furnaces of various types.

The object of the invention is to provide a fire door, which can be easily opened, and which will automatically close, the door being formed in upper and lower sections suitably connected together, and the upper section lifting vertically and being heavier than the lower section the weight of the upper section automatically lifting the lower section into closed position when the doors are released.

The invention consists of the novel features of construction hereinafter fully described, pointed out in the claim and shown in the accompanying drawings in which,

Figure 1 is a face view of the door in closed position. Fig. 2 is a side elevation 30 a portion of the furnace frame being in section. Fig. 3 is a horizontal section taken upon the line 3-3 of Fig. 2. Fig. 4 is a vertical section through the door, the sections being in partly open position. Fig. 35 5 is a detail view, a portion of the frame being in section.

In these drawings, 1 represents the front wall of the furnace or fire box, provided with the usual coal opening 2. Fitting 40 around this opening is a frame 3, which frame is hinged at one end as shown at 4, and provided with a suitable catch 5, at the opposite end which engages a keeper 6, carried by the wall 1. This frame swings in 45 a horizontal plane, and when thrown back the opening 2, is cleared of all obstruction thus permitting ready entrance for the purpose of cleaning out. This frame is in the form of a rectangular box the ends of which 50 project in advance of the sides and are oppositely and obliquely cut-away thereby forming front oppositely inclined edges 7 and 8, the upper edge 7, being of the greater

length and inclining outwardly and downwardly, while the shorter edge 8, slants outwardly and upwardly. The corners of the frame are provided with curved faces 9, so that there will be no angles or pockets in which coal can collect.

Formed at the front corners of the frame 60 are suitable brackets 10, which form bearings for pintles 11, of the door sections 12 and 13, the section 12 being the upper section and having a greater width and surface area and therefore being heavier than 65 the section 13. These door sections rest respectively upon the edges 7 and 8, of the ends of the frame 3, and as shown in Fig. 3, these edges are beveled, and the door sections are beveled also to fit said edges 70 and are also provided with flanges 14, which lap over the sides of the frame ends. To operatively connect these door sections in unison, I provide a pivoted link 15, upon a projecting end portion of the upper pintle 75 11 of the door 12, said projecting portion being preferably formed on the left-hand side of the lower pintle 11 and upon the same side is pivoted midway its ends a link 16, the inner end of the link 16 is pivotally 80 connected to the link 15 by means of a link 18, adjustment of which is provided for by means of a suitable turnbuckle 19. To the other end of the link 16 is pivoted a link 17, which is pivotally connected to and supports a foot treadle 20.

It will be obvious that by depressing the inner end of the treadle, the link 17 will be drawn down and the link 16 rocked upon the lower pintle. As the links 16 and 15 90 are fixed by suitable set screws to the pintles upon which they are mounted, the rocking of the link 16 will swing the door section 13 outwardly and downwardly. At the same time the link 18 will be lifted, thus 95 lifting the link 15 and swinging the door section 12 outwardly and upwardly. When pressure upon the foot treadle is removed the door section 12 will drop back of its own weight, being larger and heavier than 100 the lower section 13, thus forcing the link 18 downwardly and inwardly, returning the link 16 to its normal position as shown in Fig. 2, thus closing the lower door section 13, both sections being operated by gravity although moving in opposite directions.

In order to permit adjustment on account of wear, I have provided an adjustable bearing 21 for the pintles 11, said bearing being held in the bifurcation of the bracket 10.

5 In order to permit the doors to be opened readily against the interior draft of the furnace, said doors are formed with hollow spaces 22 therein, said spaces communicating through suitable openings 23 with the 10 interior of the furnace. It will be noted therefore that as soon as the doors commence to open the exterior air can flow into the spaces 22 and through the openings 23 into the furnace, thus overcoming the pull 15 upon the doors of the inner draft, or in other words relieving the outer faces of the door of exterior air pressure since they have

been opened sufficiently to permit the outside air to pass into the spaces 22.

What I claim is:

A fire box closure comprising a frame adapted to swing upon a vertical axis, of doors arranged at an angle to each other and hinged in said frame, said doors swinging upon horizontal axes, means for causing 25 said doors to swing in unison, the upper door being of greater dimensions and weight than the lower door and falling into closed position by gravity, the two doors being operatively connected.

FREDRICK WILLIAM FRANK.
